UNITED STATES PATENT OFFICE.

WESLEY WEBBER, OF KEARNEY, NEW JERSEY.

PROJECTING DEVICE.

1,091,992.

Specification of Letters Patent. Patented Mar. 31, 1914.

Application filed November 21, 1911. Serial No. 661,595.

To all whom it may concern:

Be it known that I, WESLEY WEBBER, a citizen of the United States, and a resident of Kearney, Harrison P. O., in the county of Hudson and State of New Jersey, have invented a new and Improved Projecting Device, of which the following is a full, clear, and exact description.

My invention relates generally to projecting devices and more particularly involves an improved mechanical ball throwing machine adapted for use in playing baseball.

The principal object of my invention is to provide a new and improved machine of the class described constructed and arranged whereby the direction and curve of a projected ball may be varied.

A further object of the invention is to provide a construction having coöoperating parts thereon whereby a baseball may be thrown in a given direction and with a given curve, the speed at which the ball is thrown being variable.

A further object of the invention is to provide a new and improved machine of the class described having means for removably holding a ball in position with a moving arm carrying the ball and the said means, the moving arm when brought to rest projecting the ball forwardly.

A further object of the invention is to provide a new and improved construction of the class described which will consist of a few parts, thereby enabling it to be produced at a low cost and which will be extremely efficient in operation.

Other objects and advantages of the invention will appear as the description thereof proceeds, all of which are particularly pointed out and included in the appended claims.

Reference is to be had to the accompanying drawings forming a part of this specification in which similar characters of reference denote corresponding parts in all the views, and in which—

Figure 1 is a rear view of the device in inoperative position; Fig. 2 is a side view thereof; Fig. 3 is a sectional view on the line 3—3 of Fig. 2; Fig. 4 is a sectional view on the line 4—4 of Fig. 6; Fig. 5 is a section on the line 5—5 of Fig. 1; Fig. 6 is a section on the line 6—6 of Fig. 4; Fig. 7 is a section on the line 7—7 of Fig. 2; Fig. 8 is a perspective view of the baseball with

the strap wound thereon; Fig. 9 is a perspective view of the strap.

The apparatus is designed to be supported on any suitable stand or support 1 adapted to rest on the ground and be held in position by means of pegs or stakes 2 driven therein and engaging the corners of the support.

The projecting device as a whole is mounted on a platform 3 which rests on top of the support 1 being pivotally supported thereto at 4 and being movable with respect to the support through the medium of a toothed segment 5 having a handle 6 thereon mounted in a suitable bearing 7 at the end of the support 1, the end of the platform 3 being provided with a series of notches or serrations 8 with which the teeth on the segment 5 are adapted to engage.

Mounted on the platform 3 are the uprights 9, spaced a suitable distance apart, being held in position on the platform by means of suitable brackets 10. Extending between the uprights 9 is a shaft 11, one end of the shaft passing through a sleeve 11' having a concave gear 12 thereon with which a worm 13 mounted on a shaft 14 is adapted to engage, the outer end of the shaft being provided with a hand wheel 15 whereby it may be turned, the shaft itself being mounted in suitable bearings 16 carried by the upright. Secured to the outer end of the shaft 11 is an arm 17 having means at its upper end for removably holding a baseball in position; also secured to the shaft 11 and preferably between the uprights 9 is a wheel 18 having notches 19 on its periphery, there being a pin 20 extending transversely of the wheel and secured to one end of a spiral spring 21, the other end of this spiral spring being secured to the before-mentioned sleeve 11'.

Pivotedly supported on a suitable shaft 22 extending between the uprights 9 is a handle 100 23. Secured to an intermediate point of the shaft is a dog 24 adjustably held in position by means of a set screw 25; pivotally mounted on a stub axle 26 which extends transversely of one of the uprights 9 is a bell crank lever 27, one end 28 of which is adapted to be engaged by the dog 24, the other end 29 being normally held in engagement with one of the notches or teeth 19 on the wheel 18 by means of a leaf spring 30 held in position on a suitable pin 31 carried by the upright 9.

Referring particularly to Figs. 2 and 5, the upper end of the arm 17 is provided with a suitable opening through which the rod 32 extends, one end of which is threaded as at 33, this same end being provided with a slot 34, the forward end of the rod carrying a device which I term a cup 35 for holding a baseball 36. The cup and rod are adjustably and resiliently held in position on the arm 10 through the medium of a leaf spring 36 bearing against the rear end thereof and surrounding the rod, there being a handle 37 on the rod having a pin 38 extending therethrough and into the slot 34, the inner end 15 of the handle bearing against the spring 36, the handle itself being held in position through the medium of a nut 39.

The cup or ball holder 35 has a central cavity 40 into which the ball is adapted to 20 fit, there being a plurality of spring fingers 41 secured to the cup and adapted to engage the outside of the ball when it is positioned as shown in Fig. 5. Referring particularly to Figs. 8 and 9 it will be noted that the ball 25 36 before being positioned in the cup has a strap 50 wound thereon, this strap being concavo-convex in cross section whereby it may closely engage the outer surface of the ball, one end of the strap when the ball is 30 positioned in the cup extending through a suitable opening 42 therein and passing beneath a fastening device which embodies a cam 43 mounted on a shaft 44 having a handle 45 at one end thereof. Mounted in suitable 35 bearings 46 on the outside of the upright 9 is a bar 47 having a helical spring 48 wrapped thereon, one end of the spring being in engagement with one of the bearings while the other end engages a lug 49 carried 40 by the bar. This bar is positioned in the same vertical plane as the arm 17 and is adapted to engage therewith when the arm is thrown to discharge the ball and, to this end, the bar is provided with a resilient head 45 51, together with a number of U-shaped leather washers 52 whereby the distance which the bar moves when the arm is thrown may be varied, thereby determining the trajectory of the ball when it leaves the cup.

50 The operation and use of the machine is as follows. The stand or support is positioned as shown in Figs. 1 and 2 and the platform 3 which carries the projecting device proper is rotated about the pivot 4 until the proper direction in which the ball is to be projected is obtained. The speed at which the ball is to be projected is determined by the tension of the spring 21 carried on the sleeve 11', the tension being increased by operating the hand wheel 15 whereby the worm 13 turns the worm wheel 12, thereby varying the tension of this spring; with a greater tension the projecting device proper is brought from the dotted line position of Fig. 2 to the full line

position with greater velocity, thereby projecting the ball with greater velocity than when this spring is under a lesser tension. The strap 50 is wrapped around the ball 36 in the manner shown in Fig. 8, the ball being then placed in the pocket or cup 35 with the end of the strap extending through the opening 42 and being secured in position by turning the cam 43 through the medium of the handle 45 secured thereto. The spring 75 fingers 41 hold the ball with the strap thereon in position as shown in Fig. 5 and the cup is resiliently held in position on the arm 17 through the medium of the leaf spring 36, the rod 32 which carries the cup 80 being adjustable by turning the hand wheel 37 whereby the relation between the direction in which the end of the strap 50 extends to the trajectory of the ball may be determined, thereby enabling the ball to be projected with different spinning motions whereby the curve which the ball defines in its passage through the air is obtained. The trajectory of the ball is also determinable by the angle defined by the arm 17 with a 90 vertical plane when this arm engages the resilient head 51 on the bar 47 which is resiliently mounted in position on the upright 9, this angle being variable by varying the number of washers 52 in order to have the 95 arm 17 engage this resilient head before it comes into a vertical position or after it has passed through such position, thereby determining the distance which the ball will travel before reaching the ground and also 100 determining the height which the ball will reach in its flight. After these adjustments have been made the arm with the ball positioned thereon is brought to the dotted line position in Fig. 2, movement of the arm 105 turning the shaft 11 and with it the serrated wheel 18 and also tightening the spring 21, the arm being held in dotted line position by reason of the engagement of the lower end of the bell crank lever 27 with one of the notches or serrations 19 in the wheel 18; this engagement is maintained by the leaf spring 30 which bears against the lower end of this bell crank lever. The arm is brought from dotted line to full line position 110 by pulling downwardly on the handle 23 whereby the dog 24 which is also secured to the shaft 22 moves the bell crank lever 27 out of engagement with the notched periphery of the wheel 18 and permits the arm 115 to come into full line position with varying velocity, the reaction of the arm striking the resilient head 51, projecting the ball from the pocket 35, the ball being given a spinning or turning motion through the unwinding 120 of the strap 50.

The construction of a machine such as I have outlined provides an effective mechanical baseball pitcher and one under the control of the operator since the curvature and 130

the trajectory of the projected ball are under his control, the number of parts and the co-operation thereof being reduced to a minimum whereby as simple and effective a device is produced as is necessary to throw a baseball with the certainty desired. The size of the various parts will be sufficient to bear the necessary shocks and strains due to the operation thereof, the material of which 10 the parts are made and the design of the different parts being largely matters which may be left to the skill of the maker in producing a machine which is pleasing and attractive in its appearance.

15 Having thus described my invention, I claim as new, and desire to secure by Letters Patent:—

1. In a mechanical baseball pitcher, a support, a swinging arm, means for swinging said arm from one position to the other, quickly, a stop for arresting the movement of said arm, a cup for receiving a ball arranged on said arm, means for loosely holding said ball in said cup, means for rotatably holding said cup on said arm, a strap adapted to be wound around said ball when the same is arranged in said cup, one end of

said strap extending beyond said cup, and means for clamping said strap to said arm at any point along the strap, whereby the 30 strap may be wound to any desired extent around said ball.

2. In a mechanical baseball pitcher, a base, a swinging arm arranged in said base, means for swinging said arm quickly from 35 one position to the other, a stop for suddenly arresting the movement of said arm, a cup for receiving a ball, means for connecting said cup with said arm, a strap adapted to be wrapped around said ball when the 40 same is in said cup, and to extend from said cup, and a pivotally mounted cam for pinching said strap against said arm, said cam pinching said strap at a point intermediate the ends thereof, whereby any desired length 45 of strap may be wrapped around said ball.

In testimony whereof I have signed my name to this specification in the presence of two subscribing witnesses.

WESLEY WEBBER.
